UNITED STATES PATENT OFFICE.

ABNER SIRIS, OF BROOKLYN, NEW YORK

OILET-ARTICLE PACKAGE.

1,383,887.

Specification of Letters Patent. Patented July 5, 1921.

Application filed April 2, 1921. Serial No. 457,917.

To all whom it may concern:

Be it known that I, ABNER SIRIS, a citizen of the United States, and a resident of Brooklyn, Kings county, State of New York, have invented an Improvement in Toilet-Article Packages, of which the following is a specification.

The present invention relates to an improvement in toilet article packages, one object being to provide a package which will not only be attractive in appearance but which will also protect the article inclosed and permit inspection thereof without exposing it.

One embodiment of my invention is illustrated in the drawings accompanying the present specification and in which—

Figure 1 is a front elevation, and Fig. 2, a longitudinal vertical section.

Referring to the drawings, an article to be carried in the package such as a powder puff 1 or other toilet accessory is inclosed in an envelop made of transparent paper or other suitable material having an opening at one end to permit the insertion and removal of the article, said opening being closed by a flap 2 which may be secured in closed position by an application of mucilage or other adhesive material, or may be closed by means of a superposed sticker overlapping both the flap 2 and the rear wall of the envelop. The front wall of the transparent envelop is provided with an opening 3 and an insert 4 bearing printed or pictorial matter is positioned inside the envelop between said opening 3 and the toilet article 1 in such a manner that a portion of the printed or pictorial matter on the insert is visible directly through the opening 3 while the remainder of the printed or pictorial matter is visible through that portion of the transparent wall which surrounds the opening 3. Thus, from the foregoing description taken in connection with the drawings, it appears that a package embodying my invention provides a receptacle which permits inspection of the article through the transparent rear wall and which is also attractive in appearance, presenting a unique pictorial effect by reason of the framing of a portion of the printed or pictorial matter without sacrificing the effectiveness of the package as a protective covering. A further advan-

tage residing in the construction hereinabove described is that the package may be varied in appearance by varying the pictorial or printed portions of the insert either in subject matter or in color or in both.

This invention has successfully solved a problem incident to the sale of powder puffs, the importance of which is only suggested by a recital of the advantages flowing from the use thereof. The article to sell readily must be in a transparent package so that the purchaser can see it. At the same time, the article must be so wrapped that it cannot be handled and soiled. A transparent waxed paper envelop fills these requirements but it is not feasible to print colors on waxed paper and it seems that the consumers of powder puffs favor a dainty package having some attractively colored inscription or picture. Under these circumstances, the edge of the hole in the front wall of the envelop may serve as a frame for a small color print conveniently appearing on a card insert while the wall surrounding the hole permits the rest of the printed or pictorial matter to be seen, but in a different tone. Furthermore, where the insert is of relatively greater stiffness than the material of the envelop, its corners will project into the envelop corners and prevent the same from collapsing or losing their rectangular contour. This package has found great favor in the trade and is looked upon as a valuable contribution thereto and as a solution of a difficult selling problem.

I claim as my invention:

A toilet article package comprising in combination a powder puff, a transparent envelop inclosing said puff and through one wall of which the powder puff may be inspected, the other wall of said envelop having a hole of any desired shape, and a printed or pictorially ornamented insert interposed between the hole and the powder puff to protect the puff, to maintain the envelop in substantially extended form, and to present through the hole an unobstructed view of printed or pictorial matter on its exposed surface.

In testimony whereof, I have signed my name to this specification this 31st day of March 1921.

ABNER SIRIS.
